[57] CLAIM

The ornamental design for collapsible basket, as shown
and described.

DESCRIPTION

FIG. 1 is a top plan view of a collapsible basket showing
my new design; shown in an unfolded position, the
bottom plan view being a mirror image thereof;

FIG. 2 is a typical side elevational view thereof; and,
FIG. 3 is a perspective view thereof; shown in erected
position.

FIG. 1

FIG. 2

FIG. 3
